COAT

Otto F. Weisend, Columbus, Ohio, assignor of
one-half to Edward Miller, Columbus, Ohio

Application February 24, 1936, Serial No. 65,178

2 Claims. (Cl. 2-93)

The object of this invention is to provide an improved construction of coat in which the upper back portion is normally maintained in a smooth and unrumpled condition, and the tail or lower portion of the back at the rump of the wearer normally maintained in a spread condition.

As well known the rump of the human body is curved or rounded from the spine both laterally and rearwardly. It is therefore more particularly an object of this invention to provide the back with an improved construction tending to maintain that part of the coat with spreading or flaring effect outward from the line around the top of the rump so as to cause the tail portion normally to hang gracefully below and at the same time prevent normal movement of the tail portion, as when the wearer is walking, from disturbing or rumpling the back above. Other objects will appear from the description.

The invention is embodied in the example herein shown and described, the features of novelty being fully claimed.

In the accompanying drawing—

Figure 1 is an elevational view of the back of the coat according to the invention.

Fig. 2 is an elevation of the side of the coat.

Fig. 3 is a fraction of the back piece showing the same gathered on an arched line to effect a narrowing of the cloth.

Fig. 4 is a similar view showing an arched stay strip applied along the gathered arch line or region of the cloth.

Fig. 5 is a similar view showing an arched belt sewed to the back and covering the stay piece.

Fig. 6 is a vertical section on a larger scale on the line VI—VI Fig. 5.

The back piece 10 of the coat can be made as a single piece from the top to the lower end of the tail or of two pieces, as usual, stitched together vertically at the middle of the back by ordinary stitching, as indicated by broken line 10a in Fig. 1. Before sewing the back piece into the garment the material, after the usual wet shrinking of the cloth, is contracted at the region just above the rump by gathering it on an upwardly arched line, as indicated at 11 Fig.

3. This gathering of the cloth can be effected by means of a sewing machine employing what is termed a gathering stitch attachment, but such gathering of the cloth can be done by hand sewing. The effect of this gathering is to narrow, and to some extent stiffen the cloth, the latter according to the number of such lines employed.

After stitching by gather-stitching said back piece, as described, there is applied, as herein shown, to said piece a stay strip 13 or other suitable reinforcing material, said reinforcing piece being arched to substantially coincide with the arch of the gathering stitches, as shown in Fig. 4. This strip 12 is cut so that its lower edge is somewhat longer than its upper edge and said strip 12 is sewed by stitching 13 in a spread out condition and a corresponding spreading out of the fabric of the coat piece below the gathering stitching to thereby accentuate and maintain a bulged condition of the upper portion of the tail of the coat. The stay strip 12, instead of being sewed to the outer side of the coat fabric, as shown, can be sewed in like manner to the inner side of the back of the coat with the cloth next to it spread out.

After the staying strip has been applied, as indicated, an arched belt 14, usually of the same material and pattern as that of the back of the coat, is applied by stitching in a manner to cover the stay piece or the stitches thereof, as shown in Fig. 6. The belt 14 cooperates with the stay piece whether the latter be at the outer or inner face of the back of the coat in maintaining the bulged condition of the back at the top of the tail portion of the coat below the gathering stitching. Indeed if the fabric of the back be of suitably tight weave or material reliance can be had on the belt 14 and gathering stitching alone to produce and maintain the bulge of the tail portion of the coat.

Some pleating in the back would not interfere with the incorporation of the present invention in the coat.

It will be observed that with this construction of the back of the coat ordinary movements of the tail portion are not communicated to the upper portion of the back, the stiffening afforded by the arch and its location serving in a large measure to intercept such communication and leaving the upper back in a normal and unrumpled condition.

The forms of the parts can be changed without departing from the gist of the invention as claimed.

What I claim is:

1. A coat having in the region of the middle of its back portion an arched line of gathering stitches extending in a generally horizontal direction across the small of the back, thereby producing a fulness below said line, and a flexible reinforcing member arched conformably to said line of stitches and secured to said back portion

at said fulness and in substantially a zone parallel to said gathering stitches.

2. A coat having in its back portion in the region of its middle an arched line of gathering stitches extending in a generally horizontal direction across the small of the back, thereby producing a bulge in said back portion below said arched line of stitches and a flexible reinforcing

member for said bulge arched conformably with said line of gathering stitches and secured to the outer side of said back portion in substantially a zone parallel to said line of gathering stitches, and an arched belt of the same material as that of the back portion superimposed on and secured to said reinforced bulge. 5

OTTO F. WEISEND.
